(57) **CLAIM**

The ornamental design for a video game console grip case, as shown and described.

DESCRIPTION

FIG. 1 is a top elevational view of a video game console grip case showing my new design;

FIG. 2 is a top plan view thereof;

FIG. 3 is a bottom plan view thereof;

FIG. 4 is a left side elevational view thereof;

FIG. 5 is a rear perspective view thereof;

FIG. 6 is a front elevational view thereof;

FIG. 7 is a rear elevational view thereof;

FIG. 8 is a bottom perspective view thereof;

FIG. 9 is an exploded view thereof;

FIG. 10 is a top plan view showing the claimed design in its environment of use thereof; and,

FIG. 11 is an enlarged view of the portion of FIG. 1 outlined by the dot-dash broken line.

The evenly dashed broken lines, in FIGS. 1-3 and 9, depict portions of the video game console grip case that form no part of the claimed design. The broken lines showing of a video game controller illustrate environment structure. The dash-dot lines in FIGS. 1 and 11 depict bounds of the magnified portions and form no part of the claimed design.
